CELLULOSE SACCHARIFICATION

André Héreng, Paris, France

Application September 17, 1945, Serial No. 616,831
In France September 22, 1944

2 Claims. (Cl. 127—37)

1

This invention relates to a method for the continuous saccharification of plants.

The principal methods used for the time being for the saccharification of woody material and all cellulosic wastes by acids are discontinuous methods. They require an intermittent working equipment which is very intricate. Their efficiency remains low because the losses are always high and the regularity of the products is not insured. Continuous methods are also known which comprise a diffusion operation requiring an important battery of diffusers the working of which necessitates an abundant and expensive staff.

All these methods, whether continuous or discontinuous, comprise a regeneration of the acids which have been used, which entails the necessity of putting into play special apparatus often consisting of expensive materials such as rare metals, gold and platinum, for instance. Furthermore, they entail a very important consumption of energy and of heat.

It follows that all the known methods are expensive to install as well as to operate.

The present invention has for its object to provide a continuous method for the saccharification of plants by means of acid, which makes it possible to avoid these disadvantages and substantially to reduce the cost of the products derived and, more particularly, of alcohol, furfural and food yeasts.

Said method is characterized by the fact that the material, treated in a continuous circulation, is successively submitted to an impregnation by the liquid acid, to a treatment by the gaseous acid, which insures the concentration of the acid and the extraction of the sugars, and to a drying by the gaseous acid, which produces the recovery of the acid which has been used for the treatment.

All the difficulties arising from the discontinuous method are avoided. The efficiency is improved, the regularity of the products is obtained. Furthermore, the use of gaseous acid renders possible a considerable reduction of the equipment and a very appreciable reduction of the labour and of the consumption of energy and of heat.

Said method is suitable for all vegetable materials such as wood chips, sawdust, peat, household refuse and, in general, for all cellulosic materials. It can be used with various acids such as hydrochloric, sulphuric, formic acid or any other suitable gaseous or liquid fluid.

The single figure of the appended drawing shows by way of example a diagram of the device used for carrying out the method according to the invention. The following description relates

2 to the treatment of comminuted wood with hydrochloric acid. Of course, however, the method lends itself for any cellulose materials treated by any acid.

5 The comminuted wood is brought into the store-pit 1. It possesses a moistness of about 25%, a preliminary artificial drying of the same being not necessary. It is regularly discharged by a distributor 5 into the impregnation vat 2. The distributor 5 which is acid-tight controls the introduction of the wood. The latter when introduced into 2 is sprinkled with an excess of liquid hydrochloric acid. Said acid comes from the return 28 and from the vat 6 in which its concentration is adjusted. Said concentration varies according to the species of wood which is treated and whether or not the extraction of the pentoses is effected by a prehydrolysis as will be seen later on. A preheater 12 makes it possible to bring the acid to the suitable temperature.

10 The wood descends progressively by a simple falling action into the impregnation vat 2 whereafter it passes into the hydrolysis tower 3. The latter can be of any kind such as, for instance, 15 the so-called Gay-Lussac towers used in chemical industry. More particularly, it can be a tower of the kind which forms the subject-matter of the patent application Serial No. 616,830 filed on September 17, 1945. It is in the tower 3 that 20 the continuous diffusion is effected, the wood impregnated with acid falling down from one stage to the following one.

15 At the bottom of the tower is a chamber 37 divided into two parts one of which receives the 25 gaseous hydrochloric acid supplied by the piping 4 while the other receives the treated material and the acid in excess flowing along the successive stages of the tower 3. A discharge tube for the acids in excess collects the latter and brings them 30 to the vat 11.

20 Vat 10 is a fresh acid storage. 14 is a barometrical condenser with its cooler 13. Said condenser 35 condenses the excess of hydrated hydrochloric gas and feeds the reservoir 10 from which the acid returns to the cycle.

25 Vat 11 and circuit 27 make it possible to bring acid in excess into the tower 3 again and to concentrate it in acid and sugars.

30 A pump and pipe 8 carry the residue of the wood 50 which chiefly consists of lignin impregnated with acid and sugars into the drying-room 15, the pipe 9 being used for the return of acid removed at the point 34 in the drying room 15. The latter is preferably constituted like the tower 3. In said 55 tower the lignin falls down in a regular manner.

Through the same passes a current of gaseous hydrochloric acid in a cold condition less than 30° C. which consists of anhydrous acid brought to the bottom of the drying-room through the piping 19 and leaving at the top of said room after having been loaded with water and acid. One thus sees that through the use of gaseous acid the drying is obtained in the cold and under the atmospheric pressure. Thus, every degradation of the sugars is avoided which beyond 40° C. and in the presence of acid would be converted and become useless; this result being obtained without it being necessary to operate in vacuo as in the known methods for the recovery of acid. Simultaneously, the acid contained in the lignin is recovered without special accessory apparatuses. The dried lignin is collected on the bottom of the drying-room 15. It passes into a washer 16 where the sugars are dissolved and carried off. The lignin rises through slightly sloping ducts under the action of screws. A current of water runs down along the slope and flows several times upon the same while dissolving the sugars whereafter it is collected at 18, as very concentrated juices.

The lignin is ejected at 17.

The slightly acid juices collected at 18 are pre-heated in an exchanger 20 and brought to autoclaves 21 where the inversion of non-fermentable sugars is effected with the presence of 2% chlorhydric acid. The autoclaves are heated by steam coming from the boiler 24.

The juices are then neutralized by a base in the vat 22 which is provided with a stirring device and brought to 18° Brix in order to undergo the fermentation. In the vat 18 said juices have a concentration of 22 to 25 degrees Brix.

A room for the dehydration of the acid is shown on the right hand side of the figure.

Said room comprises vats 23 containing calcium chloride in an oversaturated solution. Said chloride absorbs the water contained in the acid and coming from the preceding treatments and supplied by the piping 19. The solution of chloride is brought to the boiler 24 in order to vaporize the absorbed water and the salt-solution is then brought back to the vats 23. The drying gas, after bubbling through 23, returns to the drier 15 in an anhydrous condition after having passed through an exchanger which makes it possible to recover its sensible heat. Said gas the temperature of which is 30° C. as a maximum is brought to the drier 15. 25 is an acid storage.

The dehydration vats 23 can be substituted by a plate-furnished column or by any other similar device.

With the above described method all the intricate and expensive apparatuses used for recovering the acid are dispensed with since the acid is extracted from the lignin itself at the ordinary temperature and the atmospheric pressure. The losses of acid are reduced to those which are necessary for the inversion at 21.

The temperature of the acid gaseous fluid is maintained in the pipings and auxiliary apparatus above its dew-point so as to avoid condensations of acid, which makes it possible to use common metals for these devices. When it is not intended to effect the extraction of the pentoses the hacked wood discharged into the tower 2 is copiously sprinkled there with liquid hydrochloric acid of 20-21 degrees Baumé. It passes through the vat 2 during about fifteen minutes. It is then distributed regularly in the tower 3. The acid in excess is taken again by the piping 28 and brought to the top of the vat 2

where a supplement coming from the vat 6 can be added.

In the tower 3 the wood which is preferably maintained in a state of constant turbulence is submitted to the action of hydrochloric gas flowing through the same in a counter-current relation. Said gas which is introduced at 4 into the chamber 37 in the lower part of the tower leaves at the top of said tower through the piping 46 after having acted upon the wood. It has passed through all the wood layers which were originally impregnated with acid of 27-33%. It is partially absorbed by said acid which, owing to this fact, is concentrated and the excess saturated with moisture leaves at 46. By this means the titre of the acid in the fibres of the wood themselves rises little by little and finally reaches about 41%. The treatment takes place in the absence of air, the atmosphere of the tower 3 being saturated with hydrochloric gas.

The method makes it possible to use ordinary commercial acid, to concentrate it at will without any special apparatus nor loss of time. The treated material is then dried at 15 by the gaseous acid, anhydrous and cold as already indicated.

When it is desired to extract the pentoses the comminuted wood introduced into the impregnation vat 2 remains there during 30 to 45 minutes. The acid of vat 6 is a little more diluted and its temperature is higher at 12 than in the preceding operation. The time of retention in the vat 2 or the capacity of said vat must be sufficient in order to permit the partial hydrolysis of the carbohydrates and the formation of pentoses in presence of acid under the action of the heat.

The juices and the wood flow regularly into the tower 3. Some of the upper stages of tower 3 are sprinkled with fresh acid or with water. The juices coming from this sprinkling are removed at 33 carrying with them the pentoses which have formed. A portion of said juices rises through 29 into vat 2 for being concentrated by a new passage and for limiting the action of the acid. The excess is removed at 30. Said excess is then absorbed by dried lignin and passes into a drying-room identical in construction with the drying tower 15 for the contained acid being there extracted down to 2%. After the washing of the lignin the juices containing the pentoses and the 2% of acid are treated in an autoclave for obtaining furfural or xylose.

In tower 3 the wood the pentoses of which have been extracted falls down further and the rising current of gaseous acid rapidly concentrates the acid in order to permit the formation of the hexoses by hydrolysis according to the already described process.

I claim:

1. A continuous method of extracting the pentoses and hexoses from comminuted wood comprising the following steps: impregnating the wood by treating it with heated liquid hydrochloric acid of 27-33% concentration for 30 to 45 minutes, thereafter treating the wood with fresh liquid acid, extracting pentose containing liquid and treating the wood therewith at an earlier stage, subjecting the impregnated material to a countercurrent of gaseous hydrochloric acid at atmospheric pressure, thereby raising the strength of the acid absorbed in the wood to 41%, drying the material with a current of anhydrous gaseous hydrochloric acid at less than 30° C. thereby reducing the acid absorbed in the wood

to not over 2%, washing the lignin hexose mixture remaining after the last step, to extract hexoses, drying the remaining lignin, absorbing the pentose liquid previously collected with the lignin, extracting the pentoses by drying the lignin pentose mixture with a current of anhydrous gaseous hydrochloric acid at less than 30° C. and washing the lignin pentose to obtain the pentoses.

2. A continuous method of extracting the pentoses and hexoses from comminuted wood which comprises the following steps: impregnating the wood by sprinkling it with heated liquid hydrochloric acid of 27-33% concentration by weight for 30 to 45 minutes, sprinkling the wood with additional hydrochloric acid, collecting the pentose containing liquid extracted by this sprinkling, subjecting the remaining impregnated material to action by hydrochloric acid in a gaseous state at atmospheric pressure thereby raising the strength of the acid absorbed in the wood to 41% and producing hexoses, moving the material while drying it in the presence of a countercurrent of hydrochloric acid in a gaseous anhydrous

state at less than 30° C., thereby reducing the acid absorbed in the wood to not over 2% and extracting water and acid, washing the materials to extract the hexoses, and recovering the used acid.
